(57) **CLAIM**

We claim the ornamental design for a fence, as shown and described herein.

DESCRIPTION

FIG. 1 is a front perspective view of a fence in accordance with the new design, the rear perspective view being a mirror-image thereof;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.
